UNITED STATES PATENT OFFICE.

WALTER H. FITZ GERALD, OF BROOKLYN, NEW YORK.

STEM-WINDING AND SETTING MECHANISM FOR WATCHES.

SPECIFICATION forming part of Letters Patent No. 338,945, dated March 30, 1886.

Application filed October 3, 1885. Serial No. 178,934. (Model.)

To all whom it may concern:

Be it known that I, WALTER H. FITZ GERALD, of Brooklyn, in the county of Kings, and in the State of New York, have invented certain Improvements in Stem Winding and Setting Watches; and I do hereby declare that the following is a full, clear, and exact description thereof, reference being had to the accompanying drawings, in which—

10 Figure 1 is an enlarged view of the parts of my mechanism separated from each other and from the case-center. Fig. 2 is a like view of the same as combined for use. Figs. 3 and 4 are plan views of a watch, and show, respectively, the positions of parts when the stem-operated train is in engagement with the winding-wheel and with the dial-wheels. Fig. 5 is a perspective view of the case-center portion of my improvements as arranged for attachment to a hunting-case; and Fig. 6 is a like view of the same when in position within a case-center.

Letters of like name and kind refer to like parts in each of the figures.

25 My invention is an improvement in stem winding and setting watches in which the winding and setting train is placed in engagement with the winding-wheel or the dial-wheels by the longitudinal movement of a rotatable stem arbor; and it consists, principally, as an improvement in stem winding and setting watches, in the combination of a rotatable, longitudinally-movable stem-arbor which has no positive connection with the watch-movement, a device that is pivoted within the case-center and adapted by a movement upon its axis to change the engagement of the winding and setting train from the winding-wheel to the dial-wheels, and an intermediate device 35 which is contained within said case-center and is adapted to communicate the longitudinal movements of said stem-arbor to said pivoted device and cause the latter to turn upon its axis, substantially as and for the purpose hereinafter specified.

40 It consists further, as an improvement in stem winding and setting watches, in the combination of a rotatable, longitudinally-movable stem-arbor which has no positive connection with the watch-movement, a device that is pivoted within the case-center, and by a movement upon its axis is adapted to permit

the winding and setting train to be disengaged from the dial-wheels and engaged with the winding-wheel, and an intermediate device 55 which is contained within said case-center and is adapted to communicate the longitudinal movements of said stem-arbor to said pivoted device and cause the latter to turn upon its axis, substantially as and for the purpose 60 hereinafter shown.

It consists, further, as an improvement in stem winding and setting watches, in the combination of a winding and setting train which is normally in engagement with the winding-wheel, a device that is pivoted within the case-center, and by a movement upon its axis is adapted to change the engagement of the winding and setting train from the winding-wheel to the dial-wheels, a rotatable longitudinally-movable stem-arbor which has no positive connection with the watch-movement, and an intermediate device that is contained within said case-center and is adapted to communicate the longitudinal movements 75 of said stem-arbor to said pivoted device and cause the latter to turn upon its axis, substantially as and for the purpose hereinafter set forth.

It consists, further, as an improvement in 80 stem winding and setting watches, in the combination of a winding and setting train which is normally in engagement with the winding-wheel, a device that is pivoted within the case-center, and by a movement upon its axis is 85 adapted to permit the winding and setting train to be disengaged from the dial-wheels and engaged with the winding-wheel, a rotatable, longitudinally-movable stem-arbor which has no positive connection with the 90 watch-movement, and an intermediate device that is contained within said case-center and is adapted to communicate the longitudinal movements of said stem-arbor to said pivoted device and cause the latter to turn upon 95 its axis, substantially as and for the purpose hereinafter shown and described.

It consists, further, as an improvement in 100 stem winding and setting watches, in a watch-case provided with a rotatable longitudinally-movable stem-arbor, a pivoted device which, by a movement upon its axis is adapted to change the engagement of the winding and setting train from the winding-wheel to the dial-wheels,

and an intermediate device that is adapted to communicate the longitudinal movements of said stem-arbor to said pivoted device and cause the latter to turn upon its axis, each of 5 said parts being connected with said case and having no positive connection with the watch-movement, substantially as and for the purpose hereinafter specified.

It consists, finally, as an improvement in 10 stem winding and setting watches, in a watch-case provided with a rotatable longitudinally-movable stem-arbor, a cam, which is pivoted within the inner face of the case-center and has gear-teeth at one point upon its periphery, 15 and a lever that is pivoted within said case-center and has one end engaged by a peripheral groove in said stem-arbor and its opposite end, which is provided with a toothed segment, in engagement with the toothed periphery of said cam, whereby a longitudinal movement of 20 said stem-arbor will cause a partial rotation of said cam, substantially as and for the purpose hereinafter shown.

In the annexed drawings, A represents the 25 "center" of a watch-case which is provided with a stem or pendant, B, and has journaled within the same an arbor, C, that is rotatable in the usual manner, and is also adapted to have a certain amount of longitudinal motion. 30 Within a groove, a, in the interior of the case-center A, at one side of and preferably about one-half inch from the inner end of the stem-arbor C, is pivoted a cam, D, which has the form shown in Figs. 1 and 2, and is provided 35 upon its periphery at the point of its smallest radial dimensions with gear-teeth d. Within the groove a, between the stem-arbor C and cam D, is pivoted a lever, E, which, as seen in Fig. 1, has upon one end a toothed segment, 40 e, that engages with the gear-teeth d of said cam, and at its opposite end e' is adapted to fit into and engage with a peripheral groove, e, which is formed within said stem-arbor near its lower end. If, now, the stem-arbor C is moved 45 longitudinally within the pendant B, its motion in such direction will be communicated to the lever E, and through the same to the cam D, and will cause the latter to have a partial rotation upon its axis. Said parts are relatively arranged so that when said stem-arbor 50 is at the outer limit of its motion said cam will have its largest portion turned inward toward the axis of the case, as seen in Fig. 4, while by moving said arbor to the inner limit 55 of its motion said cam will be turned outward to the position shown in Fig. 5.

The case thus provided is intended for the reception of an ordinary watch-movement, F, in which the winding-wheel G and dial-wheels 60 H are, when desired, connected with the stem-arbor C, by means of a pinion, I, that is engaged by the inner end of said arbor, a gear-wheel, K, which is journaled upon the movement-plate and receives motion from said 65 pinion, and two pinions, L and M, respectively, that are journaled upon a yoke, N, which is pivoted upon the axis of said wheel K. The

pinions L and M are arranged upon opposite sides of the wheel K, and are in engagement with the same, and by the movements of the 70 yoke N may be respectively brought into engagement with the winding-wheel G, or the dial-wheels H. A spring, O, operates to hold said yoke with a yielding pressure in position to cause said pinion L to engage with said 75 winding-wheel, so that the winding and setting train is normally in position for winding the mainspring.

The movements of the cam D are utilized for changing the engagement of the winding 80 and setting train from the winding-wheel to the dial-wheels by providing upon the end of the yoke N, adjacent to the pinion M, an arm, n, which extends outward to position for engagement by said cam, the arrangement being 85 such that an inward movement of said cam will turn said yoke to the position shown in Fig. 4 while, when said cam is moved outward said yoke will be turned to the position seen in Fig. 3, by the operation of the 90 spring O.

The construction described is adapted for open-faced watch-cases. For hunting-cases, where the interior of the case-center A is provided with an annular recess, a', the cam D 95 and lever E are pivoted upon a block, P, as shown in Fig. 5, which block is fitted to said recess a', and is preferably secured therein by means of screws, as seen in Fig. 6.

This improvement adapts the watch-case to 100 receive any movement which is designed for it, and renders the insertion therein or removal therefrom of a movement as easy as would be the same operation in case of key-winding watches.

Having thus fully set forth the nature and 105 merits of my invention, what I claim is—

1. As an improvement in stem winding and setting watches, the combination of a rotatable longitudinally-movable stem-arbor which has 110 no positive connection with the watch-movement, a device that is pivoted within the case center, and adapted by a movement upon its axis to change the engagement of the winding and setting train from the winding-wheel 115 to the dial-wheels, and an intermediate device which is contained within said case-center and is adapted to communicate the longitudinal movements of said stem-arbor to said pivoted device and cause the latter to turn upon 120 its axis, substantially as and for the purpose specified.

2. As an improvement in stem winding and setting watches, the combination of a rotatable longitudinally-movable stem-arbor which 125 has no positive connection with the watch-movement, a device that is pivoted within the case-center and by a movement upon its axis is adapted to permit the winding and setting train to be disengaged from the dial-wheels 130 and engaged with the winding-wheel, and an intermediate device which is contained within said case-center and is adapted to communicate the longitudinal movements of said stem-

arbor to said pivoted device and cause the latter to turn upon its axis, substantially as and for the purpose shown.

3. As an improvement in stem winding and setting watches, the combination of a winding and setting train which is normally in engagement with the winding-wheel, a device that is pivoted within the case-center and by a movement upon its axis is adapted to change the engagement of the winding and setting train from the winding-wheel to the dial-wheels, a rotatable longitudinally-movable stem-arbor which has no positive connection with the watch-movement, and an intermediate device that is contained within said case-center and is adapted to communicate the longitudinal movements of said stem-arbor to said pivoted device and cause the latter to turn upon its axis, substantially as and for the purpose set forth.

4. As an improvement in stem winding and setting watches, the combination of a winding and setting train which is normally in engagement with the winding-wheel, a device that is pivoted within the case-center and by a movement upon its axis is adapted to permit the winding and setting train to be disengaged from the dial-wheels and engaged with the winding-wheel, a rotatable longitudinally-movable stem-arbor which has no positive connection with the watch-movement, and an intermediate device that is contained within said case-center and is adapted to communicate the longitudinal movements of said stem-arbor to said pivoted device and cause the latter to turn upon its axis, substantially as and for the purpose shown and described.

5. As an improvement in stem winding and setting watches, a watch-case provided with a rotatable longitudinally-movable stem-arbor, a pivoted device which by a movement upon its axis is adapted to change the engagement of the winding and setting train from the winding-wheel to the dial-wheels, and an intermediate device that is adapted to communicate the longitudinal movements of said stem-arbor to said pivoted device and cause the latter to turn upon its axis, each of said parts being connected with said case and having no positive connection with the watch-movement, substantially as and for the purpose specified.

6. As an improvement in stem winding and setting watches, a watch-case provided with a rotatable longitudinally-movable stem-arbor, a cam which is pivoted within the inner face of the case-center and has gear-teeth at one point upon its periphery, and a lever that is pivoted within said case-center and has one end engaged by a peripheral groove in said stem-arbor and its opposite end, which is provided with a toothed segment, in engagement with the toothed periphery of said cam, whereby a longitudinal movement of said stem-arbor will cause a partial rotation of said cam, substantially as and for the purpose shown.

In testimony that I claim the foregoing I have hereunto set my hand this 18th day of September, 1885.

WALTER H. FITZ GERALD.
